UNITED STATES PATENT OFFICE.

JOSEPH FROELICH, OF NEW YORK, N. Y., ASSIGNOR TO MERGENTHALER LINOTYPE COMPANY, A CORPORATION OF NEW YORK.

SORTING MECHANISM FOR LINOTYPE-MACHINES.

No. 890,269.

Specification of Letters Patent.

Patented June 9, 1908.

Application filed June 10, 1907. Serial No. 378,270.

To all whom it may concern:

Be it known that I, JOSEPH FROELICH, citizen of the United States of America, residing at the borough of Brooklyn, city, 5 county, and State of New York, have invented certain new and useful Improvements in Sorting Mechanism for Linotype-Machines, of which the following is a specification.

10 My invention relates to an improvement in linotype machines used in printing for producing bars of metal on which forms of characters to be printed are cast.

The type of machine to which the present 15 improvement is applied is provided with a magazine adapted to hold a supply of matrices of the different characters and to maintain them separated into groups. A keyboard having a key corresponding to each 20 group is operatively connected to the magazine by a means for releasing a matrix from any group when the corresponding key is pressed. The matrix released is conducted by a suitable mechanism to its place in the 25 line and locked therein. A quantity of molten type metal is brought into contact with the line of matrices and a bar cast having on its edge characters corresponding to those of the matrices.

30 In order that the characters produced on the type bar may correspond to the keys pressed the matrices must be sorted so that each group will contain only matrices of like characters.

35 The present invention relates to means for sorting the matrices to this end and provides mechanism to which the lines of matrices are fed after having been cast and by which they are sorted into groups.

40 The object of my invention is to aid the selection of these matrices by separating them into as many groups as may be desired. My device may be used for distributing matrices for each letter into separate 45 groups, but the purpose to which I apply my invention is to effect a primary sorting of matrices into fonts or other grand divisions, leaving the distribution of matrices into character channels to a second operation. By 50 separating this operation into two stages I am enabled to consolidate the apparatus and greatly shorten the distances which the matrices have to travel, besides simplifying the means by which selection of fonts and characters is accomplished.

Figure 1 is a top plan view of the sorting mechanism broken away intermediately and at the front portion. Fig. 2 is an elevation similarly broken away and looking from the righthand side of the machine. Fig. 3 is a top plan view of the sorting mechanism drawn to a reduced scale. Fig. 4 is a vertical longitudinal section of the front end of the machine in which some of the matrices are shown in section and others in elevation, 60 showing a matrix in position to be cut off. Fig. 5 is a section in the same plane, showing a line of matrices in position to be fed to the sorting mechanism, the first matrix being depressed in position to be acted upon by 65 the ejector. Fig. 6 is a section in the same plane, showing a matrix in the position which it occupies immediately after being ejected and engaged by the conveying screws. Fig. 7 is a transverse section through the feeding 70 device on line 7—7 of Fig. 8, looking in the direction of the screws. Fig. 8 is a fragmentary view taken from the lefthand side of the machine, certain parts being broken away to show the ejector and its actuating 75 mechanism. Fig. 9 is a top plan view of the base plate and combination bar, the distributing screws and side guide being removed. Fig. 10 is an end view of the same. Fig. 11 is an elevation looking from the right, showing the base plate, the combination bar, the supporting bar, the side guide and the drop channels. Fig. 12 is a section on the line 80 12—12 of Fig. 11, looking in the direction of the arrows. Fig. 13 is a transverse section 85 on the line 13—13 of Fig. 4, looking in the direction of the arrows. Fig. 14 is a section on the line 14—14 of Fig. 4, looking in the same direction, the parts in the rear of the plane of the section being omitted. Figs. 90 15 to 22 are sections taken transversely of the combination bar, showing the different combination of wards, portions of the matrices and their coöperating nicks being shown in connection therewith. Fig. 23 is 95 a horizontal section through a drop channel taken on the line 24—24 of Fig. 13. Fig. 24 is an enlarged section on the line 13—13 of Fig. 4, showing a matrix sustained by the supporting bar over the opening to a drop 100 channel. Fig. 25 is a section in a plane parallel to that of Fig. 25 showing a matrix 105 disengaged from the supporting bar resting on the wards of the combination bar. Fig. 26 is a section on the line 14—14 of Fig. 4, 110

showing a matrix disengaged from the supporting bar, a ward on the combination bar registering with a nick in the matrix. Figs. 27 and 28 are detail views of the depressor. Fig. 29 is a detail view of the ejector. Fig. 30 is a view of the ejector shown in connection with a matrix. Fig. 31 is a view of the ejector, shown in connection with the first two matrices of the line which is being fed. 10 Figs. 32, 33 and 34 are, respectively, a side, end and top plan view of the lefthand rail of the raceway.

Similar elements are designated by similar reference characters in the different figures 15 of the drawings.

Referring to Fig. 11, the sorting mechanism consists of a base plate 1 and a combination bar 100. On the base plate is mounted at the front end a bracket 2, and at the rear end 20 a second bracket 3, both rigidly attached to the base plate. Jounaled at each end in the brackets and extending between them are three parallel distributing or conveying screws 4, 5, and 6 (see Figs. 3, 7, 13) provided with threads of equal pitch, the axes of 25 the screws 4 and 5 being in the same horizontal plane while the axes of the screws 4 and 6 are in the same vertical plane. Jounaled on a stud rigidly mounted in an arm 7 30 of the rear bracket 3 is a pulley 8 (Figs. 1, 2, 3) adapted to be driven by any suitable driving means from a convenient source of power. Rigidly connected by means of a sleeve 9 to the pulley 8 to rotate therewith is a gear 10 35 which meshes with the gears 11 and 12 rigidly mounted on the screws 4 and 6, respectively. The gear 11 meshes with the gear 13 on the screw 5 so that screws 4 and 6 rotate in one direction, in this case lefthanded, while screw 40 5 rotates in the opposite direction, or right-handed. The gears 11, 12 and 13 are of equal diameters and have each the same number of teeth, so that the distributing screws 4, 5 and 6 have each the same speed of revolution. The spiral gear 14 mounted on the forward end of the upper righthand conveyer screw 4 to rotate therewith, meshes with a spiral gear 15 rigidly mounted on a transverse shaft 16 jounaled in the bracket 50 2 so that rotary motion of uniform speed is transmitted from the screw 4 to the transverse shaft. A bell crank lever 17 (see Fig. 2) rigidly mounted on a transverse shaft 18 jounaled in the bracket 2 carries a roller 19, 55 which engages the surface of a cam 20 which is mounted on the shaft 16 to rotate therewith. The arm 25 of the bell crank lever 17 is connected by means of a spring 26 with a pin 27 in the bracket. The tension of the 60 spring tends to maintain the roller 19 in contact with the cam, so that the lever 17 and the shaft 18 are given an oscillating motion as the cam rotates.

The bracket 2 (see Fig. 1) is slotted longitudinally of the machine at 21, and in this

slot is a lever 22, which will hereafter be known as the depressor or cut-off member. This lever forms a rigid structure with the shaft 18, as shown in Figs. 27 and 28 and oscillates therewith. It extends in the direction of the feed, and in its depressed position is substantially horizontal. The rear end of this lever is provided on its under side with a forwardly disposed shoulder 23 and a downwardly disposed pressing surface 24, extending to a point well between the conveyer screws. A cam 28 (Fig. 8) is mounted on the lefthand end of the shaft 16 to rotate therewith. The cam is engaged by a roller 29 pivotally mounted on the end of one arm 80 of the bell crank lever 30, to the other arm 31 of which is connected one end of a spring 32 attached at its other extremity to a pin 33 in a stationary portion of the machine. The lever 30 is rigidly mounted on a stud 34 85 which is journaled in the lefthand side of the bracket 2 and extends inwardly to the face of the slot 21.

Rigidly mounted on the inner extremity of the stud 34 in a recess in the lefthand face of 90 the slot 21 is a lever 35 which extends downwardly from the stud 34 and is oscillated vertically by the cam 28 and the spring 32, which latter tends to maintain the roller 29 in contact with the face of the cam 28. 95

The lower end of the lever 35 is slotted to receive a pin 36 on the ejector 37 between the rails 40 and 46 near their rear ends (see Figs. 7, 8 and 13) the slot being to compensate for the arcuate motion of the lever and 100 the rectilinear motion of the pin. The pins 36 and 98 are fast in the ejector and extend through elongated holes 99 in the rail 40. These pins are provided with heads on their outer ends. The head on the pin 98 engages 105 the outer surface of the rail, while the head on the pin 36 bears against the outer surface of lever 35. Both pins guide the ejector and maintain it in contact with the rail 40. The ejector is provided with an extension 38 adapted to engage the longitudinal slot 39, Fig. 32, in the inner face of the lefthand rail 40 of the raceway 41, partially closed at its rear end by the block 42. The oscillation of 110 the lever 35 gives to the ejector 37 a reciprocating motion in a horizontal plane. Looking at the ejector (Figs. 29, 30, 31) in end elevation, as in Fig. 31, it will be seen to be provided with a vertical arm 44 which lies against the inner face of the rail 40 and at its 115 lower extremity with a laterally extending horizontal arm 43, both extending to the rear. The ejector is slotted laterally at 45 to receive the projection (110) at the lower right hand corner of each matrix. 120

The parallel rails 40 and 46 of inverted L-shaped cross section, are rigidly attached to the inner surfaces of the slot 21 in the bracket 2 and extend forwardly from the rear face of this bracket a distance depending upon the 125

length of line which it is desired to sort. Between these rails at their forward extremity is interposed a block 47 (Fig. 3) to which the rails 40 and 46 are attached, forming a rigid structure which will be termed a raceway, and the inner vertical faces of which are spaced a distance apart slightly greater than the width of the matrices. The rails 40 and 46 (see Fig. 7) are provided at their upper edge with inwardly disposed horizontal flanges 48 forming one arm of the L's, having their inner edges parallel and spaced to engage the matrices in sliding relation at the cut-away portion x, y , Fig. 24, in the sides of the matrices, so that the downwardly disposed faces 75 rest on the tops of the flanges. At their forward portions the flanges are cut away (see Fig. 3) to form the opening 49 at the forward end of the raceway equal in lateral extent to the distance between the inner flat vertical surfaces of the rails, and slightly greater than the greatest lateral dimension of the matrices. The inner faces of the rails are provided near their lower edges with slots 50, which extend substantially their entire length. A follower 51, having a base or plate 52 engaging the slots 50, slides in the space between the rails 40 and 46. This follower has a flat vertical rear surface 53, which is adapted to engage the forward member of a line of matrices which is fed by suitable mechanism into the opening 49 and between the rails of the raceway. The follower is laterally enlarged at its upper extremity 54 for the purpose of affording an extended bearing surface to the matrices. The follower is actuated by the weight 55, connected thereto by a cord 56, which passes over a pulley 57, and is attached to the bracket 58 on the base of the follower. The follower presses the matrices against the stop shoulder (62) hereinafter described, the pressure on the matrices being constant.

Extending longitudinally of the machine, intermediate of and parallel to the screws 4 and 5 and resting at its rear end on the upper surface of the bracket 3 and its forward end attached to the lower surface of a cross-bar 59 of the bracket 2, is the supporting bar 60, sometimes known as the distributor-bar. This bar is provided with a depending longitudinal central tongue or keel 61, having a vertical forwardly disposed cut-off shoulder 62 (see Fig. 11) at its forward end, and provided with longitudinally extending laterally disposed teeth 63, 64, 65 (Fig. 24) arranged in pairs, one above the other, the lateral extent of the pairs of teeth increasing from the lower to the upper pair. These teeth correspond to and are adapted to engage teeth in the matrices by which the latter are suspended in sliding relation to the bar. The teeth on the bar project outwardly while the teeth on the matrices project inwardly. The teeth on the bar are cut away at intervals, as shown

in Figs. 11 and 26, to form rectangular longitudinally extending shoulders 66, 67 and 68, having vertical lateral surfaces.

Directly beneath the supporting bar 60, formed in the base plate, and each spanned by a portion of the supporting bar which is provided with teeth, is a series of drop channels 69 equal in number to the cut-away portions of the teeth (see Fig. 11). These drop channels divide the combination bar 100 into sections. In advance of and between the drop channels the sections 70 of the combination bar 100 form ways on which the matrices may slide. These sections present at their forward extremities supporting surfaces 71, which are upwardly and rearwardly inclined. These surfaces as shown, are slightly convex. The remainder of the surface of each section is milled down to form longitudinally extending tongues 72 (see Figs. 15 to 22) which will hereafter be termed wards. The wards of each section are of different size or differently disposed from those of every other section, so that the cross section of the combination bar taken between any two apertures 73 is different from a cross section of the bar taken between every other two apertures, as shown in Figs. 15 to 22. The upper surfaces of the wards are horizontal and flush with the upper portion of the inclined forward surface. The upper surfaces of the wards and the upper surfaces of the combination bar between the wards form upper and lower guiding surfaces, so that the matrices are separated into groups, and those which register with the wards are guided in a lower path while those which do not register therewith are guided in an upper path with their teeth on a line with the teeth of the supporting bar. The combination bar 100 is provided with a side bar 73, which is cut away at 74 opposite the drop channels, as shown in Fig. 13, to allow easy access of the matrices to the drop channels.

The matrices to be used in connection with this machine (see Figs. 30 and 31) resemble in many respects those in common use in the art. The term "front" and "rear" as applied to the faces of the matrices are used in the same sense in which they are applied to the machine: The front face of a matrix is the face disposed towards the front of the machine when the matrix is engaged by the distributing mechanism. Each matrix consists of a flat block of metal, substantially oblong in outline, as seen in front or rear elevation, as in Figs. 26 and 31, and of varying thickness in accordance with the character to be formed. In the upper side is a notch 101, the sides of which are provided with teeth 84 (see Fig. 26) by which the matrix may be suspended at one period of the operation. The right and left sides of the matrix, looking at it from the rear as in Fig. 26, are recessed to form shoulders 75, 75, by which the matrix may be suspended at another period of the

operation. The recess on the right is enlarged to form a slot 83, through which the ejector extends into contact with the matrix just cut off. In the lower surface of the matrix are nicks 105 (see Figs. 15-22) of different outline and differently placed in the matrices of different groups. In the rear surface of the matrix is a slot 76 to receive the positioning means.

10 In the operation of the machine the follower 51 is drawn forward against the action of the weight and a line of matrices presented in the opening 49 between the ways and supported therein by any suitable mechanism, 15 which it is thought unnecessary to illustrate. The presenting means is withdrawn and the follower released on which the weight 55, acting through the flexible connection 56, actuates the follower to engage the matrices 20 and move them along the raceway beyond the opening 49, so that their laterally extending downwardly disposed shoulders 75 (Fig. 7) are brought into engagement with the upper surfaces of the top flanges 48 of the 25 rails 40 and 46 upon which the matrices are maintained in suspension. The forward matrix of the line is arrested in its movement by the cut-off shoulder 62 of the bar, against which the line of matrices is pressed by the 30 follower.

As previously stated, the matrices are of different thicknesses. In each matrix to be used in this machine there is a centrally located vertical longitudinal forwardly extending slot 76 of varying depth in the matrices of different thicknesses, so that the thickness of all the matrices between the bottom of the slot 76 and the front surface 77 is equal. By this arrangement the position of 40 the front surface of the first matrix is determined when the slot is engaged by the stop shoulder, and this position is the same in the case of each matrix successively, without regard to its total thickness. Thus, when 45 the first matrix of the series is brought into engagement with the cut-off shoulder 62 of the supporting bar that matrix is in position to be operatively engaged by the depressor lever, the pressing surface of which, 24, is 50 directly over the upper surface of the matrix and the vertical shoulder, 23, of which is, when the lever is brought into contact with the matrix, slightly in the rear of the plane of the front surface of the latter. By this arrangement the first matrix A, (see Fig. 4), 55 may be cut off or depressed by the downward movement of the depressor without the latter coming in contact with or disturbing the next matrix.

60 The horizontal extension 43 of the ejector 37, it will be noted, occupies a position beneath the forward matrices of the line. When in this position it serves the purpose of a safety device to support the forward 65 matrix in case it should slip out of contact

with the shoulder 62, due to its recoil when it strikes this shoulder. The ejector is now withdrawn by the action of the cam 28, the lever 30, 31, and the arm 35, so that the first matrix is unsupported thereby. As the cam 70 20 rotates it permits the depressor lever to be lowered by the action of the spring 26 and the lever 17 to the position in which it is shown in Fig. 5. The depressor is not positively, but yieldingly, actuated, so that if a matrix 75 becomes displaced or clogged neither it nor the machine is injured. The forward matrix A is engaged by the presser foot 24 of the depressor and moved out of contact with the cut-off shoulder to a position in which its 80 lower surface rests on the top surface of the combination bar near its forward extremity. The tension of the spring 26 acting on the lever 17 maintains the lower horizontal surface of the depressor in contact with the upper surface of the matrix and the latter is guided and held in upright position by this means while being moved along the combination bar to the conveyer screws. At this period of the operation the roller 19 is held 85 out of contact with the cam by the resistance of the matrix to the downward tendency of the depressor in response to the tension of the spring. The movement of the first matrix 90 of the line out of contact with the cut-off 95 shoulder allows the other matrices of the line to move in the direction of the feed till the matrix next following the one cut off takes a position with its face in contact with the shoulder 23 of the depressor lever by which 100 its movement in response to the follower 51 is arrested. This shoulder prevents the matrix just cut off from being prematurely advanced into contact with the screws by the pressure of the follower on the line. The 105 ejector is next advanced to the position shown in Fig. 6 by the action of the spring 32 on the lever 31 controlled through the roller 30 by the cam 28. This gives a yielding action which does not injure the matrix 110 or break the machine if the matrices become clogged. The cam is so timed in relation to the conveying screws that the matrix is inserted between the screws just in advance of 115 the descent of the forward ends 78, 79, 20 of 115 the threads of the screws.

Fig. 31 shows in elevation looking from the rear, the matrix A just cut off from the line and beyond it the first matrix B, remaining in the line. The slots 83 are of uniform size and similarly placed in all the matrices, so that when the matrices are in line the slots register and form an opening extending through the line. The walls of the opening are plane. In this opening the 125 ejector arm 44 reciprocates, but it does not engage the matrices when they are in line. The form of the ejector is clearly shown in Fig. 30. When the end matrix A is depressed or cut off the shoulder 75 which 130

- borders the upper portion of the slot enters the path of the ejector arm 44 and its lower portion enters the path of the horizontal arm 43, which extends backwards beneath the matrices of the line. Thus we have contact of the ejector with the matrix along the whole lower forward portion of the latter and at one point near its upper righthand corner. The extension 110 which enters the slot 45 of 5
- 10 the ejector makes it possible to provide a bearing surface extending the full width of the matrix at its base to coöperate with the horizontal arm 43 of the ejector, and forms one side of a slot adapted to receive the arm 15 44, so that contact between the ejector and the matrices is had at one side near the upper portion. The ejector thus presented to the matrix serves to advance it in an upright position as it is held by the depressor with its 20 lower surface resting on the combination bar. The block 42 is inserted in the slot 39 for the purpose of preventing the lower corner of the descending matrix from entering the said slot and thereby interrupting the action of the 25 machine. The matrix which has just been cut off and advanced horizontally by the ejector within their reach is now engaged by the threads of the conveying screws and moved thereby along the combination bar. 30 The depressor is raised by the action of the cam releasing the first matrix remaining in the line, so that the whole line is advanced by the follower, the first matrix being brought into contact with the cut-off shoulder 62. 35 It is to be observed that the matrix line is pressed constantly forward in an endwise direction, and that the foremost matrices are carried down one after another from the line and away from the detaining surface into the 40 path of the reciprocating ejector 44, by which they are advanced horizontally one at a time, within reach of the feed screws 4 and 5, by which they are carried along the distributer-bar 60, from which they are suspended. If 45 the nicks 105 in the lower edge of the matrix do not register with the wards 72 on the first section of the combination bar the matrix is supported by the wards and advanced along the guiding surface with its teeth 84 (see 50 Fig. 26) on a level with the teeth of the supporting bar. The teeth of the matrix are brought into engagement with the teeth of the supporting bar as shown in Figs. 4 and 6 before the first drop channel 69 is reached. 55 If the nicks 105 in the lower edge of the matrix register with the wards 72 on this particular portion of the combination bar the matrix will advance in the lower path, resting on the lower guiding surface of the combination bar (see Fig. 26). In this path its teeth 84 will avoid the teeth of the supporting bar, so that when the screws move the matrix to a position over the first drop channel 69 it will be without means of support 60 and will therefore enter this channel. If the 65 nicks of the matrix do not register with the wards on the section of the combination bar in advance of the first channel 69, its teeth will, as previously described, engage the teeth of the supporting bar and the matrix 70 will be suspended by the bar and carried over the channel by the screws. This operation will be repeated in the case of each matrix until it arrives at a section of the combination bar the wards of which register with the 75 nicks in its lower surface, when the matrix will follow the lower path, resting on the lower guiding surface so that its teeth do not engage the teeth of the supporting bar and it will enter into the next succeeding drop 80 channel. A channel may be provided into which all the matrices not otherwise sorted will enter. This channel should follow a portion of the combination bar on which there are no wards; or the portion of the supporting bar by which this channel is spanned may be provided with no matrix-engaging means. Each matrix will drop into the 85 channel following the portion of the combination bar with the wards of which it registers 90 and the matrices will be sorted in accordance with the nicks in their lower edges and delivered to the different channels. The number of combinations and channels may be varied and increased to separate the matrices 95 into any number of groups.
- After the matrices are separated into groups, each group commonly representing those of one font or set, they may be delivered to any suitable distributing mechanisms 100 for delivering the individual matrices to the proper channels in their magazines, these mechanisms forming no part of the present invention. The matrices of one group, however, which pass over the last drop-channel 105 69 without falling therein, will continue their course under the influence of the propelling screws along the distribution-bar 60, as indicated in Fig. 3. The distributing teeth of this bar and the corresponding teeth 110 of the matrices may be constructed and arranged in the manner set forth in U. S. patents to Mergenthaler Nos. 347,629 and 436,531. It will be observed that under this arrangement, the one distributer-bar 60 115 serves first to assist in dividing the groups or matrices into fonts, and thereafter to distribute those of one font in the usual manner. 120
- Having thus described a single embodiment of my invention, what I claim and desire to secure by Letters Patent is:—
1. In a sorting device for a linotype machine, a matrix-feeding means comprising a positioning means for engaging a slot in each matrix the depth of the slot corresponding to the thickness of the matrix, an ejector, means for moving the ejector, means for supporting a line of matrices and pressing them toward the positioning means so that the first matrix is engaged thereby, and means for disengag- 130

ing the first matrix from the positioning means, whereby it is brought into the path of the ejector.

2. In a sorting device for a linotype machine, a matrix-feeding means comprising a positioning means for engaging successively in each matrix a depression of such depth that the thickness of the matrices measured from the bottom of the depression shall be a constant quantity, an ejector, means for reciprocating the ejector longitudinally of the machine, means for supporting a line of matrices and pressing them toward the positioning means so that the first matrix of the line is engaged thereby, and means for disengaging the first matrix from the positioning means whereby it is brought into the path of the ejector.

3. In a sorting device for a linotype machine, means for conveying matrices to a plurality of channels, and a cut-off shoulder, means for pressing a line of matrices against the shoulder so that the first matrix is engaged thereby, an ejector, means for cutting off the first matrix from the line and disengaging it from the cut-off shoulder and bringing it into the path of the ejector, and a stop shoulder by which the matrices of the line are restrained from forward movement and means for actuating the ejector to bring the matrix cut off into engagement with the conveying means.

4. In a sorting device for a linotype machine, means for conveying matrices to a plurality of channels, and a positioning means, means for supporting a line of matrices and pressing them against the positioning means so that the first matrix is engaged thereby, an ejector, a depressor, and means for actuating the depressor to disengage the first matrix from the positioning means thereby cutting it off from the line and bringing it into the path of the ejector, means properly timed for actuating the ejector to present the matrix cut off to the conveying means to be operatively engaged thereby.

5. In a sorting device for linotype machine, a support, means for conveying matrices along the support, a plurality of channels in the path of the matrices, a cut-off shoulder, means for pressing a line of matrices against the shoulder so that the first matrix is engaged thereby, an ejector, a depressor, means for actuating the depressor to disengage the first matrix from the cut-off shoulder to cut it off from the line and to press the matrix against the support, and means for actuating the ejector to present the matrix to the conveying means to be operatively engaged thereby.

6. In a sorting device for a linotype machine, a conveyer, a cut-off shoulder, an ejector, yielding means for moving the ejector longitudinally of the machine, timed to coöperate with the conveyer, means for

pressing a line of matrices against the shoulder so that the first matrix is engaged thereby, and means for disengaging the first matrix from the cut-off shoulder whereby it is brought into the path of the ejector.

7. In a sorting device for a linotype machine, feeding means for the matrices comprising a means for positioning each matrix successively, an ejector, means for moving the ejector longitudinally of the machine, means for pressing the matrices against the positioning means, and means for disengaging the first matrix from the positioning means, whereby it is brought into the path of the ejector.

8. In a sorting device for linotype machines, means for feeding a line of matrices comprising means for positioning each matrix of the line successively with its front face in a predetermined transverse plane, an ejector, means for pressing the matrices against the positioning means, and means for cutting off the first matrix from the line and disengaging it from the positioning means, whereby it is brought into the path of the ejector.

9. In a sorting device for a linotype machine, feeding means for the matrices comprising a cut-off shoulder, means for pressing the matrices against the shoulder so that the first matrix is engaged thereby, an ejector extending beneath and adapted to support the first matrix, means for reciprocating the ejector, and means for disengaging the first matrix from the cut-off shoulder and bringing it into the path of the ejector.

10. In a sorting device for a linotype machine, means for conveying matrices to a plurality of channels, a cut-off shoulder, means for pressing a line of matrices against the shoulder so that the first matrix is engaged thereby, an ejector extending beneath and adapted to support the first matrix, means for reciprocating the ejector and thereby withdrawing it from beneath the first matrix, means for disengaging the first matrix from the cut-off shoulder while the ejector is withdrawn and bringing it into the path of the ejector.

11. In a sorting device for a linotype machine, means for conveying matrices to a plurality of channels, a cut-off shoulder, means for pressing a line of matrices against the shoulder so that the first matrix is engaged thereby, an ejector, means for supporting the first matrix, and means for reciprocating the ejector and withdrawing the support, means for disengaging the first matrix from the cut-off shoulder while the support is withdrawn and bringing it into the path of the ejector whereby it is presented to the conveying means.

12. In a sorting device for linotype machines, means for conveying matrices to a plurality of channels, means for cutting off a matrix from a line, and a member extending

through an opening in the matrices of the line and engaging the matrix cut off whereby the latter is brought into operative engagement with the conveyer and means for actuating said member.

13. In a sorting device for a linotype machine, means for conveying matrices to a plurality of channels, means for cutting off a matrix from the line, and an ejector having a member extending through an opening formed by registering slots in the matrices of the line, and adapted to engage the surface of the matrix's cut-off adjacent its slot and another member adapted to engage the overlapping portion of the matrix cut off, and means for actuating the ejector whereby the matrix cut off is brought into operative engagement with the conveyer.
14. In a sorting device for a linotype machine, means for conveying matrices to a plurality of channels, means for presenting a line of matrices to the conveyer, means for cutting off a matrix from the line, and an ejector extending through an opening in the matrices of the line and engaging the matrix cut off whereby the latter is brought into operative engagement with the conveyer.
15. In a sorting device for a linotype machine, means for conveying matrices to a plu-

rality of channels, means for presenting a line 30 of matrices to the conveying means, means for cutting off a matrix from the line, and an ejector a portion of which extends through an opening in the matrices of the line and engages the matrix cut off and another portion of which extends by a lateral face of the matrix of the line and engages the matrix cut off, whereby the latter is brought into operative relation with the conveyer.

16. In a sorting device for a linotype machine, means for conveying matrices to a plurality of channels, and means for feeding matrices to the conveying means consisting of a follower, a depressor and an ejector.

17. In a sorting device, a stop shoulder, 45 means for pressing matrices toward the shoulder whereby the end matrix is suspended by frictional contact therewith, an ejector, means for actuating the ejector, and means for cutting off the end matrix of the 50 line and placing it in the path of the ejector.

Signed by me at New York, N. Y., this 3rd day of June 1907.

JOSEPH FROEHLICH.
